UNITED STATES PATENT OFFICE.

HERBERT WILLIAM SORENSEN, OF LYNDON STATION, WISCONSIN.

SACK OR BAG.

Application filed February 27, 1928. Serial No. 257,361.

This invention relates to sacks or bags, and more particularly to the construction of grip tabs thereon.

The object of my invention is to lighten the work and speed up the handling of sacks used for potatoes, grain, salt, cement or like materials, which are hard or heavy to handle.

Another object of my invention is the construction of a "built-in" structure of a burlap sack, cloth sack or paper sack, producing efficient grip tabs, without the use of cumbersome straps, metal rings or clips, whereby my improved bags, when not in use, can be efficiently piled flat one upon the other, in a very satisfactory manner.

With the foregoing and other objects in view, my invention comprises certain novel constructions, combinations and arrangements of parts as will be hereinafter fully described, illustrated in the accompanying drawings, and more particularly pointed out in the appended claim.

In the drawings:

Figure 1 is a plan view of a sack constructed in accordance with my invention.

Figure 2 is an enlarged sectional view, taken on line 2—2, Figure 1, and looking in the direction of the arrows.

Figure 3 is an enlarged, fragmentary, perspective view of the sack, as it appears when filled with material, showing the grip tab ready to be gripped by the operator.

Referring to the drawings by numerals, 1 designates the whole sack, which comprises a pliable body 2 of any material, such as burlap, cloth or paper; I use the term "sack" in a broad sense, meaning any kind of a suitable container. The body 2 is provided with ordinary open end 3 and closed or inner end 4.

40 A pair of closed or "bag-like" pliable grip tabs 5 (Fig. 2) is formed at the corners of the closed end 4 by means of diagonal lines of stitching 6; these lines of stitching extend from one edge to another edge of said body, producing said closed or bag-like grip tabs 5 entirely within the marginal edges and the outer faces of said body. During these days of high cost of construction, the inexpensive manner, by stitching, of forming the bag-like 50 pliable grip tabs 5 is a decided advantage,

from a manufacturing standpoint. Further, by the novel use of the diagonal lines of stitching, no bulk is added whatsoever to the sack, and the sack is left in its original condition, for flat stacking, one upon the other, 55 which would not be possible if a cumbersome and impractical strap or a metal clip or ring was added to the body for forming a grip tab.

The lines of stitching 6 constitute a "built-in" structure, which, while durable and efficient, does not add to the bulk or weight of the sack, nor produce any obstruction to tear another sack coming in contact therewith, or injure the hand of the operator.

When the open end 3 of the body 2 is closed by a line of stitching 7 (Fig. 1), the usual grip tabs 8 are produced, whereby four grip tabs are provided on my improved sack for the efficient handling of the loaded sack by 70 two persons. However, when the empty sack is being stored, or stacked, the grip tabs 8 are not in evidence, with the flat, closed or bag-like grip tabs 5 practically oblivious, by reason of the built-in stitching, forming the tabs, 75 which produces the advantages hereinbefore assigned for my improved sack.

It is to be noted that the operator can secure an excellent grip on my pliable tabs 5, because he can "wad" or crumple the tabs up in his hands, without hurting his hands, such as an eye-structure or a metal-reinforced structure would do, although the bags and tabs in my improved structure will lie in a perfect flat condition when not in use.

While I have described the preferred embodiment of my invention and illustrated the same in the accompanying drawings, certain minor changes or alterations may appear to one skilled in the art to which this invention relates, during the extensive manufacture of the same, and I, therefore, reserve the right to make such changes or alterations, as shall fairly fall within the scope of the appended claim.

What I claim is:

As a new article of manufacture, an all-fabric sack provided at its closed end with two right angled corners only and with only diagonal lines of stitching across said two 100

corners producing closed, bag-like pliable grip-tabs of the same material as the body of the bag, and the outer edges of said grip-tabs a continuation of the marginal edges of said 5 right angled corners of the bag and capable of being wadded or crumpled in the operator's hand when the sack is filled for excellent

gripping without injury to the hand, but normally lying flat as a part of the body of said sack when the same is not filled or in use, 10 substantially as shown and described.

In testimony whereof I hereunto affix my signature.

HERBERT WILLIAM SORENSEN.
